CONTROL MECHANISM FOR PRESSING MACHINES

Clifton S. Malott, Jr., Norwood, Ohio, assignor to The American Laundry Machinery Company, Norwood, Ohio, a corporation of Ohio

Application August 1, 1938, Serial No. 222,333

9 Claims. (Cl. 192—131)

This invention relates to improvements in control mechanism for pressing machines, particularly in a control of the two-hand safety type.

5 This application is a continuation in part of my copending application Serial No. 164,455, filed September 18, 1937.

An object of the present invention is to provide in a power actuated pressing machine control means for the power means and two-hand safety manual means for actuating the control means, said manual means being arranged to load a spring means when the manuals are first actuated so that the spring means is available 15 to return the manual means to unoperated position. The control mechanism provides means actuated when the press is safely closed for unloading the spring means, whereupon the manual means remains in operated position and the 20 press remains closed.

Another object of the invention is to provide novel means for insuring the return of both manuals of a safety two-hand control to inoperative position after a pressing operation has been 25 completed and the press has been opened.

My invention encompasses not only the above mentioned structure for the purposes mentioned but the details of the control mechanism shown in the drawings and described in the specification, the essential features of which are set forth 30 in the claims.

In the drawings, Fig. 1 is an end elevation of a pressing machine embodying my invention, the parts being shown in full lines in open position, 35 in dot-dash lines in safe closed position, and in dash lines in fully closed position; Fig. 2 is a diagrammatic view of the control mechanism of the press of Fig. 1; Fig. 3 is a front elevation of the manuals and associated parts of Fig. 2 with the manual return means shown diagrammatically; Fig. 4 is a rear elevation of one of the manual controls of Fig. 2; Fig. 5 is a diagrammatic view similar to Fig. 2 showing the operated position of the parts adapted to move 45 the press parts from the full line position to the dot-dash position of Fig. 1; Fig. 6 is a front elevation of the manual means of Fig. 5; Fig. 7 is a diagrammatic view of the control mechanism in position corresponding to the dash line 50 position of the drawings of Fig. 1; while Fig. 8 is a front elevation of the manual means of Fig. 7.

While my control mechanism is applicable to many types of pressing machines, I have illustrated the same as applied to a machine com-

monly used in laundry and garment work. This comprises a frame 12 supporting a pressing bed 13 and pivotally supporting a yoke 14 adapted upon oscillation to carry head 15 into and out of engagement with bed 13 upon actuation of toggle 16 by motor 17. A spring 18 normally maintains the head in open position.

Control means is provided for supplying power to motor 17 and this control means is arranged to be actuated by two safety manuals so spaced 10 on the frame of the machine as to require a hand of the operator on each of them for their conjoint operation. Various structures are possible for arranging such a two-hand control for the control means for motor 17. In the form shown 15 I have provided a pair of valve casings 19 and 20 housing valves both of which must be operated to effectively supply fluid to motor 17. The structure is similar in the two casings and one only will be described, the parts of the other being 20 given similar suffixes. Casing 19 houses a normally closed inlet valve 19a and a normally open outlet valve 19b, both operable by actuation of valve stem 19c which has a yieldable end 19d. Upon actuation of the valves in both casings, 25 fluid is supplied through conduits 21, 22 and 23 to motor 17. If the valves in either casing are unoperated or in their normal position as shown in Fig. 2, fluid will not be supplied and the motor 17 will not be actuated.

30 Manual means is provided for actuating the valves in each casing, one manual being indicated at 25 and the other at 26. As the structure connected with these manuals is identical, one only will be described.

35 Manual 25 is rigidly connected with a sleeve 25a which is rotatably mounted on a suitably supported shaft 25b. Also rotatably mounted on the shaft is a member 25c which has a recess 25d for receiving a detent member 27. A spiral spring 40 25e has one end connected to the member 25c and the other end connected to member 25a. The arrangement of the spring is such that movement of the manual from the unoperated position of Fig. 3 to the operated position of Fig. 4 loads the spring 25e so long as the end thereof is held by the detent 27 acting through the member 25c. The sleeve 25a has a cam portion 25f adapted to engage the valve stem 19d to move 45 the valves in casing 19 to actuated position. A stop 28 engages lugs 29 and 30 to determine the unoperated and operated position of the manual respectively. The parts connected with manual 26 for engaging valve stem 20d to actuate the 50

valves in casing 20 are exactly the same as those just described.

Means is provided for withdrawing the detents 27 from the recesses 25d and 26d when the press reaches safe closed position as shown in the dot-dash lines of Fig. 1. The means shown comprises the mounting of the detents rigidly on shaft 31 which is provided with an arm 32 pivotally connected with rod 33. This rod passes through a slotted bracket 16a on toggle 16. The rod is provided with collars 33a and 33b and a spring 34 normally biases the detents 27 toward the position shown in Figs. 2 and 5.

Means is provided for insuring that both manuals return to inoperative position upon opening of the press. Each manual has associated with it power means for returning the manual to inoperative position. For instance, manual 25 is connected by rod 35a with servomotor 35, and manual 26 is connected by rod 36a with servomotor 36. Conduit 37, connecting the two servomotors, is connected by conduit 38 with valve casing 39. This casing houses a normally closed inlet valve 40, and is connected with a source of pressure fluid 41. Means is provided for momentarily opening valve 40 as the press opens. To this end the toggle knuckle carries a pivoted bellcrank 42 which has a downwardly extending arm 42a adapted to engage the stem of valve 40. As the press closes and the toggle straightens, the bellcrank turns idly in a counterclockwise direction. As the press opens and the toggle moves toward the full line position of Fig. 1, the bellcrank is held from turning by engagement with a portion 35 of the toggle knuckle. Arm 42a momentarily depresses the valve stem, opening valve 40 and sending a shot of fluid to servomotors 35 and 36. This returns manual 25 or 26 to the position of Fig. 3 if either of them was left in operated position.

With the press parts in the full line position of Fig. 1, and the control mechanism in the position of Fig. 2, the operator arranges the work on the pressing bed 13 and actuates manuals 25 and 45 26 in a clockwise direction from the position shown in Fig. 3 to the position of Fig. 6. As previously described the manuals must be jointly operated to effectively supply fluid to motor 17. The press will then start to close but in the position of the parts as shown in Figs. 5 and 6 if either of the manuals is released springs 25e or 26e will be effective to return the released manual to the position of Fig. 3, permitting the press to open. However, upon the parts reaching 55 the safe closed position shown in dot-dash lines in Fig. 1, the collar 33a is engaged by bracket 16a, moving rod 33 in a manner to withdraw detents 27 from their coacting recesses. This permits the ends of springs 25e and 26e which are 60 connected with members 25c and 26c to move in a direction to unload springs 25e and 26e. These springs are therefore no longer effective on manuals 25 and 26, whereupon the manuals may be released in the position of Figs. 7 and 8 and the press will remain closed. To open the 65 press either manual is returned to the position of Fig. 3, whereupon the cam 25f or 26f releases the valve stem 19d or 20d, permitting the valves in casing 19 or 20 to return to the position of Fig. 2, 70 evacuating the motor 17 and permitting the press to open. As the press opens bellcrank 42 opens valve 40 to cause a stroke of either servomotor 35 or 36 to return either manual from operated to inoperative position.

75 What I claim is:

1. In a pressing machine having coacting relatively movable pressing members and power means for actuating them, a control member for said power means, a manual movable between unoperated and operated positions for causing movement of said control member from power cut-off to power supply positions respectively, a spring operatively connected with said manual for loading by movement of said manual to operated position, said spring having a movable anchorage for holding it in loaded position, and means responsive to a movement of a pressing member for controlling movement of said anchorage in a direction to unload said spring. 5

2. In a pressing machine having coacting relatively movable pressing members and power means for actuating them, control means for said power means, manual means movable between unoperated and operated positions for causing movement of said control means from power cut-off to power supply positions respectively, said manual means being arranged to require conjoint use of both hands of an operator for movement to operated position, spring means operatively connected with said manual means for loading by movement of said manual means to operated position, said spring means having a movable anchorage for holding it in loaded position, and means responsive to movement of said pressing members to safe-closed position for controlling movement of said anchorage in a direction to unload said spring means. 10

3. In a pressing machine having coacting relatively movable pressing members and power means for actuating them, control means for said power means, manual means movable between unoperated and operated positions for causing movement of said control means from power cut-off to power supply positions respectively, said manual means comprising two manuals 20 spaced to require a hand of the operator on each of them for their conjoint operation, said manual means and control means being so related that conjoint operation of both manuals is necessary for movement of said control means to power supply position, each manual having a spring for returning it to unoperated position, each spring being arranged for loading by movement of its associated manual to operated position, each spring having a movable anchorage for holding it in loaded position, and means responsive to movement of said pressing members to safe-closed position for controlling movement of said anchorages in a direction to unload said springs. 25

4. In a pressing machine having coacting relatively movable pressing members and power means for actuating them, control means for said power means, manual means movable between unoperated and operated positions for causing movement of said control means from power cut-off to power supply positions respectively, said manual means comprising two manuals spaced to require a hand of the operator on each of them for their conjoint operation, said manual means and control means being so related that conjoint operation of both manuals is necessary for movement of said control means to power supply position, each manual having a spring for returning it to unoperated position, each spring having one end fastened to its associated manual and having its other end held by a releasable anchorage so that each spring is loaded by movement of its associated manual to operated position, and means responsive to movement of said pressing members to safe- 30 35 40 45 50 55 60 65 70 75 80 85 90 95 100

closed position for releasing said releasable anchorages.

5. In a pressing machine having coacting relatively movable pressing members and power means for causing relative movement thereof, a pair of control members for said power means normally in power cut-off position and both of which must be moved to power supply position for actuating said power means, a manual for 10 each control member which when in operated position will hold its associated control member in power supply position, spring means adapted to return each manual to unoperated position and arranged to be loaded by movement of said 15 manuals to operated position, said spring means having movable anchoring means for holding it loaded, and means responsive to movement of said pressing members to safe-closed position for controlling movement of said anchoring 20 means in a direction to unload said spring means.

6. In a pressing machine having coacting relatively movable pressing members and power means for causing a pressing action between them, control means for said power means, manually operated means movable between unoperated and operated positions for causing movement of said control means from power cut-off to power supply positions respectively, said manually operated means being arranged to require 25 the conjoint use of both hands of an operator for movement to operated position, springs means arranged normally to return said manually operated means to unoperated position, and means responsive to movement of said pressing members to safe-closed position for rendering said 30 spring means ineffective to return said manually operated means to unoperated position, whereby said manually operated means may be released 35

and said control means will remain in power supply position.

7. A pressing machine as in claim 5, including a power device for each manual operatively connected therewith for returning said manual to unoperated position, and means responsive to opening movement of said pressing members for supplying power to said devices. 5

8. In a pressing machine having a pair of coacting pressing members and power means for operating the same, control mechanism for said power means including two control members each of which is adapted when in inoperative position to control movement of said power means in press-opening direction, two spaced safety 10 manuals, one respectively for actuating each control member between its operative and inoperative positions, power actuated means for causing movement of each control member to inoperative position, and means responsive to opening movement of said pressing members for supplying power to said power actuated means. 15

9. In a pressing machine having coacting relatively movable pressing members and power means for actuating them, a control member for 20 said power means, a manual movable between unoperated and operated positions for causing movement of said control member from power cut-off to power supply positions respectively, energy storing means adapted to store energy 25 therein by movement of said manual from unoperated to operated position, whereupon said stored energy is effective for causing a return movement of said manual, and means responsive to a movement of a pressing member for releasing the energy stored in said last named 30 means whereby the latter becomes ineffective for causing return movement of said manual. 35
